GARMENT HANGER

La Trelle B. Glassmeyer, Cincinnati, Ohio

Application March 11, 1948, Serial No. 14,175

5 Claims. (Cl. 223—89)

1

This invention relates to a garment hanger, and more particularly to an adjustable garment hanger.

One of the objects of the invention is to provide a hanger which may be adjusted to accommodate garments of various sizes.

Another object is to provide an adjustable hanger which may be readily disassembled for shipping purposes, the component parts thereof occupying a relatively small space.

A further object is to provide a garment hanger having coat and trouser supporting portions of substantial thickness, thereby to maintain the supported garments in well-tailored condition.

Still another object is to provide a garment hanger which may be fabricated by means of a simple manufacturing process, such as molding or the like, using a non-corrosive and easily washable material, for example, a thermoplastic composition.

These and other objects and advantages are attained by the means described herein and illustrated upon the accompanying drawing, in which:

Fig. 1 is an elevational view of the hanger, shown in one adjusted position.

Fig. 2 is a bottom plan view of the same.

Fig. 3 is an exploded view of the hanger, showing its various parts in elevation.

Figs. 4 and 5 are enlarged cross-sectional views, taken on lines 4—4 and 5—5, respectively, of Fig. 1.

Fig. 6 is an enlarged cross-sectional view taken on line 6—6 of Fig. 2.

The common wire garment hanger and other similar hangers, although extensively used, have objectionable limitations. For instance, a garment having extra wide shoulders will not hang to the best advantage on a hanger of standard dimensions, the shoulders being caused to droop or bulge, or otherwise to become misshapen and lose the desired well-tailored appearance. Extra heavy garments suspended from a wire hanger or one of frail construction will cause the hanger to become distorted, which in turn causes the garment to hang out of its normal shape. The trouser supporting portion of many hangers is of thin construction, thereby effecting a deep and unsightly crease transversely of the legs of trousers supported thereon.

The foregoing and other objectionable limitations have been overcome by the device of the present invention, as will presently be shown. The exemplified hanger is preferably fabricated from a light, durable, inexpensive material, such

2

as a plastic composition, although aluminum, magnesium, or other metals may be used.

The extensible parts of the hanger may be adjusted to accommodate various sizes of garments, so that extra large sized coats or the like will hang in their normal tailored form, thereby to maintain the original lines of the garment. Because of the sturdy construction of the hanger, extra heavy garments supported thereon will not cause the hanger to become distorted. Trousers supported on the horizontal trouser suspending portion will not become transversely creased because of the extra thickness of said horizontal portion.

15 The preferred embodiment of the hanger, as shown in Fig. 1, comprises four main parts, a support member 9, two extensible angle members 10 and 12, substantially V-shaped, and a connecting bar 13. The support member 9, which may include integral suspension means, such as a hook 14, is provided with a pair of downwardly diverging legs 15 and 16, the angle formed by said legs being substantially the same as the angle of a garment shoulder.

20 The diverging legs 15 and 16 may be bifurcated for substantially their entire length to provide each leg with a pair of elongated tines 18 and 19 (cross-sectioned in Fig. 5) in spaced parallelism. The tines 18 and 19 are adapted to slidably engage or telescope into the longitudinal grooves 20 and 21 provided on opposed faces of the oblique arms 22 and 23 of the angle members 10 and 12, respectively.

25 The connecting bar 13 is also bifurcated at opposite ends thereby providing elongated horizontal tines 26 and 27 in spaced parallelism, these tines being of substantially the same length as the tines 18 and 19 on the support member 9.

The horizontal tines 26 and 27 are adapted 30 to slidably engage or telescope into cooperating grooves 28 and 29 provided on opposed faces of the horizontal arms 30 and 31 of the angle members 10 and 12, respectively, as shown in Fig. 4.

35 The grooved portions of the angle members 10 and 12 are substantially I-shaped in cross-section, as illustrated in the various sectional drawings. As shown therein, the various grooves in the angle members 10 and 12 are slightly larger than the cooperating tines in cross section, in order to permit free sliding movement therebetween.

40 By shifting the angle members 10 and 12 toward or away from each other simultaneously, any desired adjustment in the width of the hanger may be obtained, within the structural limits of the

hanger. The hanger may be held in any extended position by means of pins 35 projected through suitable apertures provided in parts of the hanger.

As shown in Fig. 3, the webs 32 of the horizontal arms 30 and 31 are provided with a series of spaced transverse apertures 33, which may be selectively aligned with a similar aperture 34 provided at each terminus of the connecting bar 13. A key or pin 35 may be projected through aligned apertures 33 and 34 for maintaining the hanger in any selectively extended position as delineated in Figs. 1 and 2.

In order to preclude spreading of the tines 18-19 and 26-27 and thereby causing possible displacement from their cooperating grooves when the hanger is in fully extended position, suitable clips 36 may be fixed to said tines adjacent their outer termini. As shown in Figs. 4 and 6, these clips may be substantially U-shaped in cross section, each leg 38 thereof being cemented or otherwise fixed to an outer face of the tines. The clips 36 are of sufficient depth to provide a channel 39 between the lower faces of the tines and said clips, thereby to permit passage therethrough of the lower sections of the angle member's arm 22-23 and 30-31 during adjustment operations.

If a rigid material is used for fabricating the hanger, the clips 36 may not be required for maintaining each set of tines in fixed parallelism. If the hanger is fabricated of a resilient material, however, clips 36 may be desirable.

The apices 40 of the angle members 10 and 12 are preferably rounded, as shown, in order to conform to the shoulder contours of a garment, and the bight of each angle member may be provided with a reinforcing web 41.

The solid median portion 42 of the connecting bar 13 may be of enlarged thickness, as shown in Figs. 1 and 3, said thickness being substantially that of the horizontal arms 30 and 31, in order to provide a flush appearance when the hanger is in its fully contracted position.

The corners of the coat supporting sections 45 and the trouser supporting section 46 of the hanger may be rounded, as shown at 48 in Fig. 5, thereby to preclude undue creasing of garments suspended thereon.

For shipping or storage, the hanger may be disassembled, as shown in Fig. 3, in which condition it occupies a relatively small space. This is of great advantage in reducing storage and shipping costs. A simple, inexpensive process, such as molding may be employed in manufacturing the hanger. Because of its sturdy construction, the hanger of the present invention will support one or more garments of extra heavy weight without danger of distortion to the hanger or the garments.

It is to be understood, of course, that various structural changes and modifications may be made within the scope of the appended claims, without departing from the spirit of the invention. It will be appreciated that the keys or pins 35 may be simply in the form of projections on the ends of leaf springs attached at or near the clips 36, to enter the aligned apertures 33 and 34; or if desired, other types of retaining means may be employed for the purpose of maintaining the required positions of adjustment of the angle members 10 and 12 relative to the connecting bar 13. If pins such as 35 are used, they may be insured against loss or misplacement by means of light chains or cords fastened to the

hanger and to the heads of the pins. Other forms of retainers will at once suggest themselves to those who are skilled in the art of mechanics.

I claim:

1. In an extensible garment hanger, the combination of a support member having a pair of downwardly diverging arms, means for suspending said support member, each of said arms being bifurcated, a pair of substantially V-shaped portions, each of the arms of each V-shaped portion having an end section of I-shaped cross-section, an arm of each V-shaped portion being engageable for lengthwise sliding with an arm of the support member, a substantially straight connecting bar, said connecting bar having a median portion and opposite bifurcated arms engageable for lengthwise sliding with the other arms of the V-shaped portions, and means for adjustably holding said support member, V-shaped portions, and connecting bar in assembled relation.

2. In an extensible garment hanger, the combination of a support member having a pair of downwardly diverging arms, means for suspending said support member, each of said arms being bifurcated, a pair of substantially V-shaped portions, each of the arms of each V-shaped portion having an end section of I-shaped cross-section, an arm of each V-shaped portion being engageable for lengthwise sliding with an arm of the support member, a substantially straight connecting bar, said connecting bar having a median portion and opposite bifurcated arms engageable for lengthwise sliding with the other arms of the V-shaped portions, and U-shaped clips about each bifurcated arm to prevent spreading of the bifurcated arms.

3. In an extensible garment hanger, the combination of a support member having a pair of downwardly diverging arms, means for suspending said support member, a pair of substantially V-shaped portions, an arm of each V-shaped portion being engageable for lengthwise sliding with an arm of the support member, the other arm of each V-shaped portion having a plurality of longitudinally spaced transverse bores across an end section, a substantially straight connecting bar, said connecting bar having a median portion and opposite arms engageable for lengthwise sliding with the transversely bored arms of the V-shaped portions, each of the arms of said connecting bar containing a transverse bore adjacent a free end of the arm, each of said bores being registerable with bores across the end section of a V-shaped portion, and a pair of keys slideable through said bores to hold the hanger in assembled relation.

4. In an extensible garment hanger, the combination of a support member having a pair of downwardly diverging arms, means for suspending said support member, each of said arms being bifurcated, a pair of substantially V-shaped portions, each of the arms of each V-shaped portion having an end section of I-shaped cross-section, an arm of each V-shaped portion being engageable for lengthwise sliding with an arm of the support member, the other arm of each V-shaped portion having a plurality of longitudinally spaced transverse bores across the central member of the I-shaped end section, a substantially straight connecting bar, said connecting bar having a median portion and opposite bifurcated arms engageable for lengthwise sliding with the transversely bored arms of the V-shaped portions, each of the arms of said connecting bar containing a

transverse bore adjacent a free end thereof, each of said bores being registrable with bores across an end section of a V-shaped portion, a pair of keys slideable through said bores to hold the hanger in assembled relation, and U-shaped clips about each bifurcated arm to prevent spreading of the bifurcated arm.

5. In an extensible garment hanger, the combination of a support member having a pair of downwardly diverging arms, means for suspending said support member, a pair of substantially V-shaped side portions each having an arm engaged for sliding lengthwise along one of the arms of the support member, the other arms of the V-shaped portions extending in aligned relation, a substantially straight connecting bar having opposed arms engaged for sliding lengthwise along the aligned arms of the V-shaped side portions, whereby four pairs of engaged relatively slideable arms are provided, an arm of each pair

10 15 20

being bifurcated, the other arm of each pair having an end of I-shaped cross-section slideable between the bifurcations of the first arm of the pair, and means for adjustably holding said support member, V-shaped portions, and connecting bar in assembled relation.
